UNITED STATES PATENT OFFICE.

THOMAS T. JAKOBSON, OF LOS ANGELES, CALIFORNIA.

MUSIC-LEAF TURNER.

1,311,123.

Specification of Letters Patent. Patented July 22, 1919.

Application filed February 28, 1917. Serial No. 151,522.

To all whom it may concern:

Be it known that I, THOMAS T. JAKOBSON, a citizen of the United States, residing at Los Angeles, in the county of Los Angeles, 5 State of California, have invented certain new and useful Improvements in Music-Leaf Turners, and I do hereby declare the following to be a full, clear, and exact description of the invention, such as will enable 10 others skilled in the art to which it appertains to make and use the same.

This invention is an improvement in music stands and has particular reference to a music leaf turner.

15 An object of the invention is the provision of an apparatus which may be easily and quickly assembled and compactly folded and which includes a novel mounting for the music leaf engaging frames which are 20 adapted to be swung independently about their pivots to turn each successive leaf or sheet of music.

Another object is to provide a novel support for the music rack and leaf engaging 25 frames whereby the same may be properly positioned on a piano in front of the player.

Other objects will appear in the details of construction and arrangements described in the specification annexed hereto.

30 The inventive idea involved is capable of receiving a variety of mechanical expressions, some of which are found in the accompanying drawings, wherein:—

Figure 1 is a front elevation of one form 35 of the invention.

Fig. 2 is a central vertical sectional view.

Fig. 3 is a front elevation of another form 40 of the invention.

Fig. 4 is a fragmentary detail perspective 45 view of a portion of a music rack showing the means for maintaining certain members of the rack in extended position.

Fig. 5 is a transverse sectional view of one 50 of the fastening devices carried by the leaf turning frames.

Fig. 6 is a fragmentary perspective view 55 of one of the auxiliary frames used in connection with the music rack.

Fig. 7 is a perspective view of a device 60 for supporting the music rack on a piano.

Fig. 8 is a fragmentary central vertical 65 section of the construction shown in Fig. 3.

Fig. 9 is a transverse section on the line 70—9 of Fig. 8.

Fig. 10 is a slightly modified form of connection. 55

Referring to the drawings and more particularly to the embodiment of the invention shown in Fig. 1, the numeral 15 indicates a sectional standard of any type to which 60 is connected the usual tripod 16. The standard 15 has, at its upper end, an extension 17 which engages in a bracket 18 carried by the rear face of the central vertical member 19 of the music rack which is generally indicated by the numeral 20. This music rack is of any preferred construction and includes the pivotally connected rack members 21, side arms 22 and connecting links 23. 70

Associated with the rack members 21 is a fastening device for maintaining the said members 21 in their extended positions and said device preferably includes a plate 25 of substantially rectangular formation and 75 having one of its edges cut to provide the spaced lugs 26 which are bent over upon the body portion of the device and which receive between the same and said body portion the edges of the rack members 21, 80 said lugs being arranged on both sides of the central vertical member 19. When in this position the portion 27 of the plate 25 between the lugs 26 will engage the rear face of the central member 19. This fastening device also provides a pivot for the swinging leaf engaging arms generally indicated by the numeral 28 and for this purpose the rear of the plate 25 is provided with a plurality of small tubes or sockets 24 corresponding in number to the number of frames 28, each socket being adapted to receive the lower inturned end 30 of one of the frames 28. 90

Each of the frames 28 comprises the relatively adjustable sections 31 and 32, the horizontal arms 33 of the latter section being in the form of tubes having flared ends so as to telescope with the horizontal arms of the section 31, the latter having buffers or stops 100 34 thereon for limiting the inward movement of the section 32. Connecting the outer ends of the arms 33 of each frame is a vertical arm 35, preferably in the form of an elongated strip of metal and having secured 105 thereto at intervals the upper and lower fastening devices 36 which are similarly constructed. Each device is in the form of a

sleeve member 37 embracing the arm 35 and having extending therefrom one arm 38 of a clip, the other arm 39 thereof being pivoted thereto and spring pressed so that the 5 vertical edge of a sheet of music may be securely retained between said arms 39 and adjacent portion of the member 37. It will be apparent that by constructing each frame of relatively adjustable sections the outer 10 section may be adjusted to accommodate the frame to different sizes of sheet music.

The upper inturned end 40 of each of the frames 28 is pivotally mounted in one of the 15 sockets or tubes 41 formed upon the rear face of the supporting element 42, said sockets 41 corresponding in construction and number to the sockets 24. The supporting member 42 is preferably in the form of a sleeve closed at its upper end and adapted 20 to receive the upper end of a central member 19 of the rack whereby said member 42 may be readily detached from said member when desired. It will thus be apparent from the 25 foregoing description that each of the frames 28 is pivotally mounted in the elements 24 and 42 so that the same may be swung independently of each other from one side of the rack to the other side carrying with them the sheets of music which are attached thereto. The element 42 has secured to one face 30 thereof a plate 43 which extends beyond the upper end of said element and which is provided at its upper end with an extension 44 having a plurality of openings 45 therein arranged at various distances from the body 35 portion of the plate 43. Any one of these openings 45 is adapted to receive the upper end of a center sheet engaging rod 46 which extends longitudinally of the central member 19 in spaced relation thereto and has its 40 lower end mounted in any one of a number of openings 47 formed in a plate 48 secured to the plate 25 and extending laterally therefrom, said rod 46 extending between the inner ends of the rack members 21. This rod 46 is employed for the purpose of facilitating 45 the turning of the sheets of music and provides a hinge for each sheet as the same is being turned, and it will be apparent that by the provision of the openings 45 and 47 the rod 46 may be adjusted laterally relative 50 to the member 19 so as to provide for the mounting of sheets or books of music of different thicknesses between said rod and said 55 member 19.

In the form of the invention shown in Fig. 3 the supporting element 42' which corresponds to the element 42 is of slightly different construction and consists of a pair of plates 43' which receive therebetween the upper end of the central member 19 of the rack, said plates being secured to said member by means of the bolts 44' and wing nuts 45', said bolts extending through an elongated slot 46' formed in the member 19. It

will be apparent from this construction that by removing the wing nuts and bolts, the element 42' may be readily detached from the member 19. The rear of the plate 43' has a number of sockets 47' secured thereto 70 and similar in construction to the sockets 41 of the element 42.

A pair of auxiliary frames 50 similar in construction are associated with the rack 20 and preferably include arms 51, have 75 their adjacent ends pivoted as indicated at 52, each arm of the lower frame being provided with clips 53 for engaging certain of the connecting links 23 of the rack whereby said auxiliary frame is supported in 80 position. The upper auxiliary frame 50 may also be provided with clips similar to the clips 53, or the same may have guide brackets 54 which receive the upper ends of the vertical arms 22 of the rack, in 85 which case the frame is supported in position by means of cap members 55 which are connected to the brackets 54 by the flexible elements 56, said caps being mounted over the upper end of said arms 22 as shown in 90 Fig. 1. In each instance the arms 51 of the frame 50 extend horizontally a considerable distance beyond the vertical arms 22 and are thus arranged in the path of movement of the arms 35 of the frames 28 and 95 thus provide stops therefor to prevent excessive swinging thereof. The outer end of each arm 51 has secured thereto one end of a flexible chain or cord 57 the other end of which carries a clip or fastening device 58 100 employed for the purpose of securing the outer sheets or covers of the music to said arms 51.

Referring now to Fig. 7 there is shown a rack supporting device employed for the 105 purpose of mounting the music rack 20 on a piano in proper position and said supporting device preferably includes a rod 59 adapted to rest upon the top of the piano transversely thereof and having an extension 60 at the rear end thereof which engages the rear of the piano. Adjustable longitudinally of the rod 59 and secured thereto by means of a nut 61 is a telescoping sleeve 62 the forward end of which has secured thereto the depending supporting rod 63 extending downwardly in a diagonal direction so as to properly incline the rack 20 which is secured thereto. This rod 63 has adjustably mounted thereon a sleeve member 65 which carries the brackets 66 to which is secured the central member 19 of the rack 20 by means of the fastener 67.

In Fig. 10 there is shown a slightly modified means of attaching the auxiliary frames 125 50 to the side arms 22 wherein the brackets 54, as shown at the left in Fig. 1, are dispensed with and the arms of the auxiliary frame have, at 54', pivoted thereto the arm 55' having upon its free end a cap member 130

56' which receives therein the upper end of the arm 22, said cap member 56' being formed by bending a pair of oppositely disposed lateral extensions of the arm 55' upon 5 themselves to form a socket.

What is claimed is:—

1. A music leaf turner comprising a rack including a central member, rack members pivoted thereto, a fastening plate for maintaining said rack members in extended position and including lugs formed upon one edge thereof and engaging said rack members on each side of said central member, a supporting element adjustably mounted 10 upon said central member, and to which a plurality of leaf engaging frames are pivotally connected.
- 15 2. A music leaf turner comprising a rack

including a central member, rack members pivoted thereto, a fastening plate for maintaining said rack members in extended position, a supporting member mounted upon said central member and including a sleeve for receiving the upper end of said central member and a plurality of tubes carried by 20 said sleeve, and tubes also carried by said fastening plate, said tubes in the supporting element and fastening plate receiving the ends of leaf engaging frames.

In testimony whereof, I affix my signature, in the presence of two witnesses.

THOMAS T. JAKOBSON.
